UNITED STATES PATENT OFFICE.

BRUCE WILLHIDE, OF GRAFTON, WEST VIRGINIA, ASSIGNOR OF ONE-HALF TO JAMES R. DEEGAN, OF BELLAIRE, OHIO.

PISTON-CYLINDER.

1,048,018.

Specification of Letters Patent.

Patented Dec. 24, 1912.

Application filed December 9, 1911. Serial No. 664,818.

To all whom it may concern:

Be it known that I, BRUCE WILLHIDE, a citizen of the United States, residing at Grafton, in the county of Taylor and State 5 of West Virginia, have invented a new and useful Piston-Cylinder, of which the following is a specification.

The present invention relates to improvements in piston cylinders, the primary object of the invention being the provision of 10 a cylinder especially adapted for use in connection with explosive and steam engines, pumps, air compressors, and the like, the body of the cylinder being preferably made 15 of cast iron as are also the heads thereof, the said body being provided with longitudinally disposed bores therethrough while the heads are provided with both longitudinally and radially disposed bores, said bores 20 providing means for permitting air to be circulated therein to cool the cylinder and heads.

A further object of the present invention is the provision of a piston cylinder, the 25 body and heads of which are provided with longitudinal and radial bores, said body and head being preferably made of cast iron, and having wrought iron tubes disposed within the respective longitudinal and radial 30 bores of the cylindrical body and heads to provide for the passage of air and at the same time reinforce the structure and reimburse the cylinder and heads for the weakness due to the bores formed therein.

35 With the foregoing and other objects in view which will appear as the description proceeds, the invention resides in the combination and arrangement of parts and in the details of construction hereinafter described 40 and claimed, it being understood that changes in the precise embodiment of invention herein disclosed can be made within the scope of what is claimed without departing from the spirit of the invention.

45 In the drawings—Figure 1 is a longitudinal sectional view through a complete piston cylinder made according to and embodying the present invention. Fig. 2 is a section taken on line 2—2 thereof. Fig. 3 is a section taken on line 3—3 thereof.

In the drawings, the numeral 1 designates

the cylindrical body of a piston cylinder which as shown is provided with a plurality of longitudinally disposed bores 2 drilled or otherwise formed through the body thereof 55 and having mounted therein the wrought iron tubes 3 whose ends 4 and 4' project beyond the ends of the bores of the cylindrical body and enter the longitudinal bores 60 a formed in the respective heads 5 and 6 of 60 the piston cylinder. The respective heads are provided with the radially disposed bores 9 in which snugly fit the wrought iron air conducting tubes 8 which open into the respective wrought iron tubes 3 at the projecting ends 4 and 4' through the apertures 7 and 7' respectively. By this means it will be seen that the air is permitted to circulate through the respective open ends of the radial and longitudinal tubes and that the 70 cylinder and heads are properly cooled to prevent the super-heating or burning out thereof. Where these bores are formed in cast iron cylinders, cast iron cylinders being the most economical, the walls thereof 75 or portions adjacent to the bores are weakened to such extent that it is necessary to produce a compensating means or reinforcement at such point and for this purpose the wrought iron tubes 3 and 8 are employed. The projecting ends 4 and 4' of the respective wrought iron tubes 3 will also 80 act as a connecting means to hold the respective heads 5 and 6 relatively to the cylindrical body 1 of the cylinder. 85

What is claimed is:

1. A piston cylinder, having a cylindrical body and a head disk at each end thereof, the walls of said cylindrical body being provided with a plurality of bores longitudinally thereof, said heads being provided with longitudinal bores to register with the longitudinal bores of the body and with a radial bore to each longitudinal bore thereof, and reinforcing tubes disposed in the 95 bores of said cylindrical body and heads.

2. A piston cylinder, having a cast iron cylindrical body and a cast iron head disk at each end thereof, the walls of said cylindrical body being provided with a plurality 100 of bores longitudinally thereof, said heads being provided with bores to register with

the longitudinal bores of the body and with
a radial bore to each longitudinal bore there-
of, and a wrought iron reinforcing tube ex-
tending through each bore of said cylin-
5 drical body and having its end in alined
bores of the heads.

In testimony that I claim the foregoing

as my own, I have hereto affixed my signa-
ture in the presence of two witnesses.

BRUCE WILLHIDE.
